(57) **CLAIM**

The ornamental design for a fuel/water separating filter, as shown and described.

DESCRIPTION

FIG. 1 is a perspective view of a fuel/water separating filter, particularly showing the inventive design thereof;

FIG. 2 is a side elevation view thereof;

FIG. 3 is a top view thereof;

FIG. 4 is a perspective view of an alternate embodiment thereof; and,

FIG. 5 is a side view thereof.

The broken line shown is for illustrative purposes only and forms no part of the claimed design.
